United States Patent Office

Des. 226,413
Patented Mar. 6, 1973

226,413

CHAIR

Jacques Guillon, Montreal, Quebec, Canada, assignor to
Jacques Guillon Designers Inc., Montreal, Quebec,
Canada

Filed May 21, 1971, Ser. No. 145,994

Term of patent 14 years

Int. Cl. D6—02

U.S. Cl. D6—55

FIG. 1 is a perspective view of a chair showing my new design;

FIG. 2 is a rear elevation thereof;

FIG. 3 is a front elevation thereof;

FIG. 4 is a side elevation; and

FIG. 5 is a top plan view thereof.

I claim:

The ornamental design for a chair, substantially as shown.
